CHARLES DICKINSON, OF MARICOPA, CALIFORNIA.

PUMP FOR OIL-WELLS.

No. 901,282.

Specification of Letters Patent.

Patented Oct. 13, 1908.

Application filed December 20, 1907. Serial No. 407,449.

To all whom it may concern:

Be it known that I, CHARLES DICKINSON, a citizen of the United States, residing at Maricopa, in the county of Kern and State of California, have invented a new and useful Pump for Oil-WellS, of which the following is a specification.

In pumping oil wells, and especially with thick oil or where there is considerable sand, 10 great difficulty is frequently encountered in operating the pump owing to the liability of the sand, shale and other sediment getting into the pump and the pump casing and thereby clogging the same to such an extent 15 that it is impossible to reciprocate the piston. Ordinarily this condition of affairs necessitates the removal of the entire pumping mechanism and cleaning the same, after which the parts are again inserted in the 20 well. Besides consuming a great deal of time and incurring considerable expense, the loss of oil during the cessation of the pumping operation amounts to considerable and in some places the character of the oil and 25 the abundance of the sand renders it necessary to repeat the operation of removing and cleaning the pump at short intervals, frequently every day, and sometimes oftener.

The principal object of my invention is to 30 avoid these difficulties by providing pumping mechanism in which it is almost impossible to clog the same to such an extent as to render it impossible to operate the piston and in case of its being absolutely necessary 35 to remove the operative parts of the pump, I so construct the same that they can be easily removed from the well, cleaned or repaired, and quickly re-inserted.

In the accompanying drawings, which illustrate one form of the invention; Figure 1 is a broken, vertical, sectional view of an oil well provided with my improved pump, showing the plunger in its elevated or operative position. Fig. 2 is a vertical, sectional view of the pumping mechanism with the plunger in its lowered position in which the end of the sinker engages with the top of the working barrel and forces it into its seat. Fig. 3 is a bottom end view of the working 50 barrel and standing valve seat.

Referring more particularly to the drawings, which are for illustrative purposes only and, therefore, are not drawn to any particular scale: 1 indicates the ordinary tubing which is inserted into a well 2 and may be of any ordinary construction and needs no fur-

ther explanation. Within the tubing 1 is arranged a pump casing 3 which also may be of any ordinary construction and be secured at the upper end by the usual clamping means 4. Secured to the lower end of the casing, is a coupling 5, having its bore or inner surface flared upwardly and outwardly, as at 6, within which is secured a yielding packing 7, preferably formed from 60 lead or Babbitt metal. The upper end of the packing is thicker than the lower end and its bore or inner surface is also preferably flared or tapered upward and outward so as to receive the enlarged upper end of the working 65 barrel 8 as shown at 9. The upper end of the coupling 5 is preferably recessed to form a shoulder 10 against which the lower end of the casing 3 is adapted to rest or abut, and the lower end is also preferably recessed to 70 form a downwardly extending lip or projection 11, which has a sharp edge that is adapted to form a shoe that can be used in the same manner as the ordinary shoe when the pumping plunger has been drawn up out 75 of the way. In this manner the coupling becomes a combined barrel seat and shoe.

Secured to the lower end of the working barrel 8 is a standing valve seat 12, which is 80 preferably in the form of a plug that is 85 screwed into the lower end of the barrel and is provided with a central bore or perforation 13 and with a transverse slot 14 in its lower end for screwing it into and out of the working barrel 8. A valve 15 is adapted to 90 rest upon the seat 12 in the ordinary manner and is confined by a cage 16. The plug or seat 12 is preferably provided with two shoulders 16' and 16'', one of which fits against a shoulder 17 formed by recessing 95 the lower end of the barrel 8, and the other shoulder is adapted to be engaged by the lower end of the cage 16, when the parts are assembled. A pin 18 is removably seated in registering perforations in the plug 100 and working barrel for preventing the plug from becoming accidentally unscrewed and lost.

Reciprocally mounted in the working barrel 8 is a hollow piston 19 which forms the pump plunger and which is provided at its upper end with a valve seat 20, upon which is loosely mounted the valve 21, which is also confined by a cage 22. The valve is reciprocated by a rod or cable 23, which may be connected directly to the cage 22 in the ordinary manner, but I preferably provide a

sinker 24 which insures the parts sinking through the heavy oil and sand which is liable to be encountered. The sinker is preferably connected with the plunger 19, or cage 22, by means of a stem 25 which is of a less diameter than the sinker, and the sinker is of a greater diameter than the upper end of the plunger 19 so as to seat the same without danger of knocking out the standing valve 15 seat, the stem 25 being of such a length that the lower end of the plunger 19 cannot engage with the standing valve 15 when the sinker engages with the upper end of the barrel 8.

15 The pump plunger 19 is preferably connected with the standing valve seat 12, as by means of what is known as the Garbutt attachment, which comprises a rod 26 that is connected with the cage 16 at its lower end 20 in any ordinary manner, and has its upper end provided with a head or enlargement 27 that is adapted to engage with shoulders, as a collar 28, at the lower end of the plunger 19 and thereby lift the standing valve 12 upward when the pump plunger is drawn out of the well. The cages are preferably connected with their operating means by screw threaded joints through which pins 29 and 30 are passed for the purpose of preventing their being separated, and especially by the twisting or rotation of the cable 23. Pins 31, are also preferably provided for locking the cages and plunger against being accidentally unscrewed.

35 By constructing the parts of a pump in the above described manner, it will be evident that the diameter of the plunger must necessarily be considerably less than the diameter of the casing, which will afford 40 considerable of space within the casing, up which the material is gradually lifted by the reciprocation of the pump plunger. This excess of area or capacity of the casing over the capacity of the plunger will prevent the 45 accumulation of sand and sediment within the casing to such an extent as to pack around the reciprocating parts and thereby hold them against movement. If it should be desirable, at any time, to remove the 50 pumping plunger and its accessories, when it is drawn upward the Garbutt attachment forms a connection between it and the working barrel through the standing valve seat and will cause the working barrel to be lifted 55 out of its leaden seat and entirely out of the well if desired, or only far enough to permit the sediment in the bottom of the casing to run back into the well, after which the plunger and working barrel can be lowered 60 into their operative positions and the work proceeded with, with but little loss of time and labor. When the pump is being lowered into the well the lower end of the working barrel readily enters the upper end of 65 the flaring seat and after the enlarged upper

end engages with the seat the sinker is then dropped a few times onto said upper end which will seat the barrel so firmly that it will not work loose during the process of pumping.

7 By lifting the plunger and working barrel entirely out of the casing, the lower end of the casing is opened to such an extent that other tools may be lowered into the well below the casing, as for cleaning out the well, etc. Or the casing can be lowered and the sharp edge of the coupling 5 can be utilized as an ordinary casing shoe for cutting any rock or other obstruction in case it is desired to sink the well deeper.

8 The plunger and working barrel may be readily disconnected by unscrewing the standing valve at the bottom of the working barrel after which the other parts of the pump may be as readily taken apart or disassembled, thereby permitting access being had to any part for the purpose of cleaning or repair.

9 In connecting the parts together, the pump plunger is assembled in the ordinary manner and inserted into the working barrel until the lower end of the Garbutt attachment projects from the lower end of the barrel. The cage and standing valve are then screwed onto the attachment and the valve is then screwed into the lower end of the working barrel and the pump is ready to be lowered into the well.

10 The lead packing is comparatively inexpensive and can be quickly seated in the tapered bore 6 and will engage with the working barrel with sufficient friction to hold the latter stationary under ordinary conditions, but will readily permit of the barrel being drawn upward with the upward movement of the pumping plunger. It will also prevent the presence of sand or other sediment from interfering with the proper seating of the working barrel when the latter is lowered into position and in case it should become worn or rendered defective, it can be readily replaced and the pump thereby made as good as new at that point.

Having described my invention I claim:

1. In a pump for oil wells, a working barrel adapted to be removably seated at its upper end by frictional contact at the lower end of the casing, a perforated plug removably secured in the lower end of said barrel having a shoulder at its lower end for engaging with the lower end of said barrel and provided with a valve seat at the upper end of said perforation, and reciprocatory pumping mechanism connected with said plug so as to remove the latter by unseating said upper end when the pumping mechanism is drawn upward beyond its normal limit.

2. In a pump for oil wells, a working barrel adapted to be removably seated at its up-

per end by frictional contact at the lower end of the casing, a shouldered perforated plug secured in the lower end of said barrel and having a valve seat at its upper end, one of said shoulders engaging with the lower end of the working barrel, a cage engaging with the other shoulder, a rod connected with said cage having its upper end provided with a head, and a valved reciprocating plunger within the working barrel having its lower end provided with shoulders which are adapted to engage with said head and lift the valve seat and unseat said working barrel when the plunger is drawn upward.

3. In a pump for oil wells, a casing provided with a tapering seat at its lower end, a yielding metallic packing within said seat having an upwardly expanded bore, a working barrel therein having its upper end enlarged externally and detachably engaging with said packing by frictional contact, and a reciprocating pumping plunger within the working barrel and of considerably less internal diameter than the casing and connected with the working barrel at its lower end, whereby the latter may be unseated and drawn upward when the pumping plunger is drawn upward.

4. In a pump for oil wells, a casing provided with a tapering valve seat in its lower end, a working barrel therein having an enlarged tapering upper end to fit said seat and be secured therein by frictional contact, a standing valve secured to the lower end of said working barrel, and provided with a headed rod, a hollow plunger reciprocally mounted in the barrel provided with a valve

at its upper end and with a shoulder at its lower end adapted to engage said head, a stem secured to the upper end of said plunger, and a sinker secured to the upper end of said stem of greater diameter at its lower end than the top of the working barrel and adapted to engage with the upper end of the working barrel and drive it into its seat, the length of said stem being such that the lower end of the plunger will be at a distance above the standing valve when the sinker is in contact with the top of the working barrel.

5. In a pump for oil wells, a casing, a shoe secured to the lower end of the casing having a sharp cutting edge at its lower end, a shoulder at its upper end for engaging with the end of the casing, and a tapering bore, a yielding metallic packing in said bore having an upwardly expanding bore, a working barrel having its upper end enlarged externally to engage with said packing, a valve secured in the lower end of said barrel, reciprocating pumping mechanism within said barrel connected with said valve and adapted to remove the barrel by withdrawing said mechanism, and means connected with said mechanism for engaging with the upper end of the barrel and forcing the same into said packing.

In testimony whereof, I have hereunto set my hand at Los Angeles, California, this 13th day of December 1907.

CHARLES DICKINSON.
